REFINING MACHINE

Edward H. Cumpston, Jr., Pittsfield, Mass., assignor to
E. D. Jones and Sons Company, Pittsfield, Mass., a corporation of Massachusetts

Application May 29, 1953, Serial No. 358,438

10 Claims. (Cl. 92—26)

This invention relates to apparatus for breaking up material and more particularly to apparatus for defibering materials such as chips, rags, etc., and for refining material such as paper-making pulp.

Objects of the invention are to provide a machine which will circulate material of high consistency, which requires less circulating power than prior machines, which has a wide range of severity of working action, which is simple and inexpensive to manufacture, and which is durable and reliable in use.

Machines according to the present invention are characterized by a generally cylindrical chamber having an inlet at one end and an outlet at the other end, a rotor mounted coaxially in the chamber, together with means at one end of the chamber for driving the rotor and means for feeding pulp into the chamber from the inlet, the rotor having peripheral rakes to work the pulp and throw it against the periphery of the chamber in the form of a thin cylindrical layer, the rakes being disposed in close juxtaposition to the periphery of the chamber to dig into the cylindrical layer and cause it to rotate, the periphery of the chamber being unobstructed to permit rotation of the cylindrical layer, whereby the centrifugal force of the rotating cylindrical layer produces a lengthwise flow which is directed toward the outlet by the pressure of the incoming pulp. The rotor preferably comprises a shaft upon which is mounted a series of disks having serrated peripheries to form the aforesaid rakes. In the preferred embodiment the disks are mounted on the shaft at an angle so that they wobble as they rotate and they are spaced close enough together to sweep over substantially the entire periphery of the chamber as they wobble back and forth.

For the purpose of illustration one embodiment is shown in the accompanying drawings in which

Fig. 1 is a plan view;

Fig. 2 is a section on line 2—2 of Fig. 1;

Fig. 3 is a section on line 3—3 of Fig. 2;

Fig. 4 is a section on line 4—4 of Fig. 2;

Fig. 5 is a section on line 5—5 of Fig. 2;

Fig. 6 is a section on line 6—6 of Fig. 2;

Fig. 7 is a section on line 7—7 of Fig. 2;

Fig. 8 is a side view of a modification showing parts in section;

Fig. 9 is a section on line 9—9 of Fig. 8; and

Fig. 10 is a section on line 10—10 of Fig. 8.

The particular embodiment shown in Figs. 1 to 7 comprises a base in the form of two channels interconnected at intervals by plates 2 welded to the channels. Mounted on the base intermediate its ends is a cylindrical chamber 3 having feet 4 secured to the base by means of bolts 6. As shown in Fig. 3 the upper side of the cylindrical chamber is cut away at the inlet end to accommodate an inlet casing 7 which may be welded to the chamber or otherwise secured in place. Fitted over the outlet end of the chamber is a casing 8 which is mounted on the base with screws 9 and which is open at the bottom to permit discharge of the refined pulp. At the opposite ends of

the base are bearings 11 and 12 which are mounted on the base by means of screws 13 and 14. Journalled in the bearings is a shaft 16 having a projecting end for connection to a motor. Fast to the shaft at the inlet end 5 is an abutment ring 17 and threaded on the shaft at the outlet end is an abutment nut 18. Fitted over the shaft intermediate the ring 17 and the nut 18 are the working parts of the machine now to be described.

At the inlet end a tube 19 is fitted over the shaft 16 with one end abutting the ring 17. Fast to the periphery of the tube 19 is a spiral rib 21 for feeding pulp into the chamber 3. Abutting the end of the tube 19 is an impeller 22 in the form of two blades 22 arranged at right angles and welded together, the ends of the blades being bent along the lines 23 so that the blades also tend to feed the pulp into the chamber 3. Spaced from the impeller 22 by a spacing ring 24 is a banger 26 having ribs 27 fast to the inlet side and notches 28 in its periphery, this device serving to break up the entering chips or other pieces of material, thereby protecting the refining elements.

Following the banger 26 is a series of serrated disks 31 which are spaced from each other by spacing rings 32, the first disk being spaced from the banger 26 by spacing ring 33. The disks preferably turn in the direction opposite to the direction in which the rakes point so that fibers and the like do not catch on the teeth. As shown in Fig. 2 the disks are mounted at an angle to the axis of the rotor so that they wobble back and forth as the shaft rotates, the disks being close enough together to sweep over substantially the entire periphery of the chamber as they wobble back and forth and far enough apart to act independently on the pulp. Mounted on the outlet end of the shaft is a retarder 34 comprising a plate having its ends bent along lines 36 (Fig. 7) in the direction to retard the flow of pulp to the outlet and prevent surging. The retarder may also have ribs 37 welded to the outlet side to assist in discharging the pulp through the outlet. The retarder 34 is held in spaced relationship to the last serrated disk by means of a spacing ring 38 and another ring 39 bridges the space between the retarder and the abutment nut 18. After the parts have been fitted over the shaft the abutment nut 18 is applied to clamp the parts between it and the abutment ring 17. After the parts have been mounted on the shaft the shaft is inserted into the chamber through the outlet end. After the shaft is mounted in the bearings 11 and 12 the housing 8 is applied over the outlet end of the chamber.

In operation the material delivered to the inlet is fed by the spiral rib 21 and impeller 22 to the banger 26 where the larger pieces are broken up. As the material passes through the rake section it is further broken up and thrown out against the periphery of the chamber 3 in the form of a thin cylindrical coating. As the coating builds up to a thickness greater than the spacing between the periphery of the disks and the periphery of the chamber the disks rake the coating and cause the coating to rotate, the periphery of the chamber being unobstructed to permit the cylindrical layer to slide. The centrifugal force produced by this rotation tends to flatten the layer and inasmuch as it cannot flatten by circumferential flow it flattens by axial flow. While the centrifugal force tends to produce axial flow equally toward the inlet and outlet ends, the flow toward the inlet end is counteracted by the incoming pulp. Consequently the flow is toward the outlet end.

From the foregoing it will be evident that most of the dispersing and refining action takes place in the thin layer in the form of high speed impact. The refining action is most pronounced when the material being worked is of high viscosity and the layer is thin. Paper-making ma-

terials can be worked to advantage at consistencies up to approximately fifty percent. At these high consistencies turbulence is held to a minimum.

The modification shown in Figs. 8 to 10 is similar to the first embodiment in that it comprises a generally cylindrical chamber 41, an inlet casing 42, a drive shaft 43, a feed screw 44 and revolving rakes 46. However it differs in the following respects. The diameter of the feed drum 44 more closely approximates the internal diameter of the chamber 41 and the radial dimension of the feed screw is less, thereby feeding the material to the chamber near its periphery. Moreover the chamber 41 is slightly tapered toward its outlet end so that the clearance between the rakes and the periphery of the chamber gradually decreases toward the outlet end. In this way the degree of refining action is gradually increased from the inlet end of the rake section to the outlet end. Furthermore the rakes 46 are pivotally mounted on rods 47 which are mounted on the rotor at their ends as illustrated at 48 in Fig. 8. In normal operation the rakes would occupy the radial position shown in the figures due to centrifugal force, but if a rock or other obstruction should be fed into the machine accidentally the rakes can swing back when they engage the rock, thereby preventing damage to the rakes.

As illustrated in both embodiments the leading edges of the ends of the rakes should incline outwardly and rearwardly, that is outwardly and in the direction opposite to the direction of rotation.

The operating conditions of these machines afford many advantages. The power consumption is relatively low due to the absence of excessive turbulence because of the small amount of carrying fluid required. The severity of the working action can be easily controlled because the high viscosities permit the use of large easily controlled working clearances. The rate of flow through the machine is controlled solely by the input rate. The severity of the refining action can be adjusted by altering the working clearances, the material viscosity, the machine speed or the shape of the rakes. The axial dimensions of the rakes should be small, preferably of the order of one-tenth inch or less. For maximum refining action successive rakes lengthwise of the chamber should be spaced apart far enough to drag through the surface of the cylindrical layer of material without substantial dragging action on the material windway between the successive teeth. The spacing between the tips of the rakes and the periphery of the chamber should be of the order of 0.01" to 0.20". The linear velocity of the rakes may vary widely depending upon the material being worked and the degree of refining desired, but for ordinary refining of paper-making material it can be of the order of 4000 feet per minute.

From the foregoing it will be understood that the cylindrical layer of material on the periphery of the chamber tends to maintain a constant thickness under constant working conditions. As the layer increases in thickness the rakes get a better hold on the cylindrical layer, thereby increasing the centrifugal force and therefore the rate of flow. Conversely if the layer tends to get thinner, due for example to a reduced rate of supply, the spinning action and centrifugal forces are reduced, thereby permitting the thickness of the layer to increase.

It should be understood that the present disclosure is for the purpose of illustration only and that this invention includes all modifications and equivalents which fall within the scope of the appended claims.

I claim:

1. A refining machine comprising an approximately cylindrical chamber having an inlet at one end and an outlet at the other end, a rotor mounted coaxially in the chamber, means at one end of the chamber for driving the rotor, and means for feeding material into the chamber from said inlet, the rotor having peripheral rakes to throw the material against the periphery of the chamber in the form of a cylindrical layer, the rakes being spaced from

the periphery of the chamber but disposed in juxtaposition to the periphery to drag through the cylindrical layer, refine it, and cause it to rotate, and successive rakes lengthwise of the chamber being spaced apart far enough to drag through the coating without substantial dragging action on the material midway between the successive rakes, the periphery of the chamber being free of obstructions which would prevent rotation of the cylindrical layer, said outlet extending around the chamber and outwardly to said periphery so that the cylindrical layer can flow directly through the outlet lengthwise of the container, whereby the centrifugal force of the rotating cylindrical layer produces a lengthwise flow which is directed toward the outlet by the pressure of the incoming material.

2. A machine according to claim 1 further characterized in that the rakes are pivoted on the rotor to swing back and permit the passage of objects which might damage the rakes.

3. A refining machine comprising an approximately cylindrical chamber having an inlet at one end and an outlet at the other end, a shaft extending axially through the chamber, a series of thin disks mounted on the shaft, means at one end of the chamber for rotating the shaft and disks, and means for feeding material into the chamber from said inlet, the peripheries of the disks being serrated to form rakes which throw the material against the periphery of the chamber in the form of a cylindrical layer and the rakes being spaced from the periphery of the chamber but disposed in juxtaposition to the periphery to dig into the cylindrical layer, refine it and cause it to rotate, said outlet extending around the chamber and outwardly to said periphery so that the cylindrical layer can flow directly through the outlet lengthwise of the container, whereby the centrifugal force of the rotating cylindrical layer produces a lengthwise flow which is directed toward the outlet by the pressure of the incoming material.

4. A machine according to claim 1 further characterized in that the leading edges of the rakes incline outwardly and rearwardly.

5. A machine according to claim 1 further characterized in that the chamber is slightly tapered so that the clearance between the rakes and chamber gradually decreases toward the outlet end.

6. A refining machine comprising an approximately cylindrical chamber having an inlet at one end and an outlet at the other end, a shaft extending axially through the chamber, a series of disks mounted on the shaft, means at one end of the chamber for rotating the shaft and disks, and means for feeding material into the chamber from said inlet and throwing it against the periphery of the chamber in the form of a cylindrical layer and the peripheries of the disks being spaced from the periphery of the chamber but disposed in juxtaposition to the periphery to drag through the cylindrical layer and cause it to rotate, so that the centrifugal force of the rotating cylindrical layer produces a lengthwise flow which is directed toward the outlet by the pressure of the incoming material, the disks being mounted on the shaft at an angle, so that they wobble as they rotate, and said outlet extending around the chamber and outwardly to said periphery so that the cylindrical layer can flow directly through the outlet lengthwise of the container.

7. A machine according to claim 3 further characterized in that said disks are mounted on the shaft at an angle so that they wobble as they rotate, and in that they are close enough together to sweep over substantially the entire periphery of the chamber as they wobble back and forth.

8. A refining machine comprising an approximately cylindrical chamber having an inlet at one end and an outlet at the other end, a shaft extending along the axis of the chamber, and means on the shaft for throwing material against the periphery of the chamber in the form of a cylindrical layer and then working on the layer, said means comprising a series of rakes disposed in juxtaposi-

tion to the periphery of the chamber to drag through the cylindrical layer and cause it to rotate, so that the centrifugal force of the rotating cylindrical layer produces a lengthwise flow which is directed toward the outlet, and said outlet extending around the chamber and outwardly to said periphery so that the cylindrical layer can flow directly through the outlet lengthwise of the container.

9. A refining machine comprising an approximately cylindrical chamber having an inlet at one end and an outlet at the other end, a shaft extending along the axis of the chamber, and means on the shaft for throwing material against the periphery of the chamber in the form of a cylindrical layer and then working on the layer, said means comprising a series of rakes disposed in juxtaposition to the periphery of the chamber to drag through the cylindrical layer and cause it to rotate, so that the centrifugal force of the rotating cylindrical layer produces a lengthwise flow which is directed toward the outlet, and said rakes being spaced from said periphery to provide clearance for fibers.

10. A refining machine comprising an approximately cylindrical chamber having an inlet at one end and an outlet at the other end, a shaft extending along the axis

5
